UNITED STATES PATENT OFFICE

GOTTFRIED RAUSCH, OF AMMENDORF, NEAR HALLE-ON-THE-SAALE, GERMANY

DOUGH DIVIDING AND WORKING MACHINE

Application filed March 31, 1928, Serial No. 266,293, and in Germany September 24, 1928.

My invention relates to dough-dividing and working machines, and more particularly to machines in which the dough is first compressed, then divided and then worked in the cells of a divider, being shaped to form round units by relative displacement of the cells and a dough-supporting plate.

A machine of this general type has been described in my co-pending application Serial No. 167,500, and the present invention relates more particularly to the means for handling the presser head which contains the presser plate and the divider, with the cells between the dividing knives. Preferably the presser head is pivotally supported on the frame of the machine so as to be lowered onto the dough supporting plate after the dough to be treated has been placed on the plate, and to be raised from the plate for removing the finished balls of dough. The presser head is rather heavy and must be handled during each operation of the machine, that is many times every day. In order to facilitate this, the presser head is preferably balanced by weights, and it is an object of my invention to so arrange the weights that the space required for the machine, and particularly the floor space, is not increased by the weights. This is important as in bakeries the floor space is as a rule very restricted.

It is another object of my invention to provide power-impelled means for handling the presser head.

The desired arrangement of the balance weights with a view to reducing the floor space required is obtained by providing between the presser head and the balance weight or weights a mechanism for reversing the relative movements of the presser head and the weight or weights. Preferably the mechanical power-actuated means for moving the presser head are connected with this gear, and means are preferably provided for automatically breaking this connection when the presser head has arrived in its upper final position. With these and other objects not specifically mentioned

in view, the invention consists in certain constructions and combinations which will be hereinafter fully described and then specifically set forth in the claims hereunto appended.

In the drawings affixed to this specification and forming part thereof a machine embodying my invention is illustrated diagrammatically by way of example.

In the drawings,

Fig. 1 is a front elevation of the machine,
Fig. 2 is an end elevation, viewed from the right in Fig. 1,

Fig. 3 is an elevation of the upper part of the machine, viewed as in Fig. 2, but partly in section, and

Fig. 4 is an elevation of the upper part of the machine, viewed from the right in Fig. 2.

Referring to the drawings, 30 is the frame of the machine, 1 is a pedal pivotally supported near the base of the frame, 2 is a shaft also supported near this base, 3 is a check on a boss of the shaft 2 which is adapted to be engaged by a projection at the end of the pedal 1, 4 is a handle keyed on the shaft 2 which is held in its initial position by the projection of the pedal 1, 5 is a rod which is pivoted to a short arm on the shaft 3 at one end and to a cross head 6 at the other, 7, 7 are rods arranged at either end of the cross head 6, 8, 8 are camways secured on the frame, 9, 9 are hooks at the ends of the rods 7 which are guided by the camways 8 through the medium of pins, and 10, 10 are lugs on a presser plate 11 which are adapted to be engaged by the hooks 9 when the cross head 6 is pulled down.

19 is the presser head in which the plate 11 can be displaced and is held in its upper end position by means of a spring 16 (Fig. 1) to which the plate 11 is returned as soon as the hooks 9 have released its lugs 10 after pressing, and 12 is a handle which is pivotally supported on the top of the presser head 19 and adapted to displace axially the divider in which cells are formed by the knives 15, the knives being able to move in slots of the presser plates 11.

18 is a dough supporting plate which is supported on a table 31 at the top of the frame 30 and adapted to receive an exchangeable dough plate 34. Mechanism is provided for imparting rotary movement to the dough supporting plate 18 with respect to the presser head 19, such mechanism comprising a driving pulley 26, a shaft 17, bevel gearing 36 and 37, a clutch 35, and a shaft 17', which is supported in bearings below the dough supporting plate 18 and can be operatively connected with the bevel gear 37 by the clutch 35. 17" are bevel gears on the shaft 17' which mesh with bevel gears 41' on short shafts 41 supported in bearings of the frame 30 below the plate 18, and 42 are crank pins on each shaft 41 engaging bosses 18' on the lower face of the plate 18.

20 The parts above described are substantially the same as in the machine forming the subject matter of my co-pending application aforesaid, but in the new machine means are provided in connection with the handle 4 for controlling the clutch 35. The part 39 (Fig. 2) is a projection on the cross head 6, and 40, 42^a is a bell crank lever fulcrumed at 71 in the frame 30 and adapted to be engaged by the projection 39 at one end and to engage the movable sleeve of the clutch 35 with the other end. When the handle 4 has been returned to its initial position, after the pressing operation has been completed, and is turned a little farther to the left in Fig. 1, the projection 39 engages below the end of the lever 40 and the clutch 35 is thrown in so that rotation is imparted to the dough-supporting plate 18. When the handle 4 is released, the clutch is thrown out by the weight of the lever 40 or by a spring (not shown).

25 20 are brackets projecting from the presser head 19 at its rear, that is, the side opposite the handle 4, 21 are eyes at the ends of suitable brackets 30' of the frame 30, 21 is a shaft which connects the brackets on the presser head and on the frame, 54 are toothed sectors on the shaft 22, 55 are spur 30 gears which are free to turn on the driving shaft 17, 50, 50 are arms secured to the spur gear 55, 49 is a balance weight on each arm, and 48 are setscrews for varying the position of the weights on their arms 50. 55 The leverage of the weights 49 with respect to the hinged shaft 22 and the presser head 19 is considerable so that the weights 49 can be small and, by bending their arms 50 from the rear toward the front of the machine, the balancing parts are arranged within the floor area of the machine so that no additional ground floor area is required for the weights.

60 The presser head 19 is readily raised by 65 its handle 28, being balanced by the weights

49, but it is preferable to effect the handling of the presser head by power-impelled means, and such means will now be described. Referring to Fig. 4, each spur gear 55 is provided with a clutch part 56, and 70 a clutch part 57 which is fitted to slide on the shaft 17 can be connected with the corresponding part 56 through the medium of a handle 58 which is pivoted to the frame 30. The clutch parts 57 are provided with 75 the usual annular grooves, as shown in Fig. 4, in which engage forks or yokes 61 secured to a shift bar 62 extending at right angles to the hand lever 58 and pivoted to said lever at 63 at some distance from the pivot 64, by which the lever is pivoted to the frame. It will be understood by those skilled in the art that one of the yokes 61 is pivoted to the frame of the machine intermediate the clutch parts and the shift bar, 85 and is also pivotally secured to said shift bar (not shown), or is otherwise arranged in any suitable way so that one yoke moves in an opposite direction with respect to the other yoke. Thus, by operation of the hand lever, the clutch parts 57 will be moved axially along the shaft to engage or disengage the clutch parts. The shaft 17 rotates at all times in the same direction and serves only for raising the presser head, 90 the head being lowered manually or by gravity.

95 Preferably automatic means are provided for throwing out the parts 57 when the presser head 19 has arrived in its upper final position. I may for instance provide projections 54' at each sector 54 which can engage lugs 58' connected with the handle 58 so as to displace axially and to throw out the two parts 57, as shown in Fig. 4. 100

105 It will be understood that the direction in which the presser head 19 is rocked about the shaft 22, is reversed by the sectors 54 and the spur gears 55 so that the weights 49 move in opposite direction to that in which the presser head 19 is moving. In this manner it is possible to arrange the weights 49 and the presser head 19 on the same side of the shaft 22, not on opposite sides, so that the weights do not project 110 from the machine, which would require 115 more floor space.

120 I wish it to be understood that I do not desire to be limited to the exact details of construction shown and described for obvious modifications will occur to a person skilled in the art.

I claim:—

125 1. A dough-dividing and working machine comprising a frame, a presser head pivotally supported on said frame, a driving shaft, a toothed sector on said presser head, a spur gear on said driving shaft meshing with said sector, a balance weight secured on said spur gear, and means for 130

operatively connecting said driving shaft with said spur gear.

2. A dough-dividing and working machine comprising a frame, a presser head 5 pivotally supported on said frame, a driving shaft, a toothed sector on said presser head, a spur gear on said driving shaft meshing with said sector, a balance weight secured on said spur gear, means for oper- 10 atively connecting said driving shaft with said spur gear, and automatic means connected with said presser head for throwing out said connecting means.

3. A dough-dividing and working machine comprising a frame, a presser head 15 pivotally supported on said frame, a driving shaft, a toothed sector on said presser head, a spur gear on said driving shaft meshing with said sector, a balance weight 20 secured on said spur gear, a clutch adapted to connect said spur gear positively with said driving shaft, means for throwing in said clutch, and automatic means connected with said presser head for throwing out 25 said clutch.

4. A dough-dividing and working machine comprising a frame, a presser head pivotally supported on said frame, a driving shaft, a toothed sector on said presser head, 30 a spur gear on said driving shaft meshing with said sector, a balance weight secured on said spur gear, a clutch adapted to connect spur gear positively with said driving shaft, means for throwing in said clutch, 35 and a projection on said presser head adapted to throw out said clutch when said head is in its upper final position.

5. In a dough dividing machine, the combination with a dough support, of a presser 40 head pivotally mounted to swing toward and away from said support, of a continuously rotating driving element, and means operable at will to connect said driving elements to said head to swing the head about 45 its pivot.

6. In a dough dividing machine, the combination with a pivotally mounted presser head, of a continuously rotating driving element, mechanism operative to connect 50 said head and element to lift the head, and means for automatically disconnecting said mechanism when the head has been lifted to a predetermined position.

7. In a dough dividing machine, the combination with a pivotally mounted presser head, of a continuously rotating driving element, mechanism operative to connect said head and element to lift the head, and means for automatically disconnecting said 60 mechanism when the head has been lifted to a predetermined position, said means including a clutch, a clutch shifter for said clutch, and an element on said head for actuating said shifter.

8. A dough dividing and working ma-

chine comprising a frame, a presser head pivotally supported on said frame, working means under said head, pressing means in said head, means for operating said pressing means toward and away from said working means, a driving shaft, a clutch for connecting said driving shaft with said working means, mechanism operatively connected with the means for operating said pressing means acting to throw in said clutch after said pressing means has been withdrawn from said working means.

9. A dough dividing and working machine comprising a frame, a presser head pivotally supported on said frame, working 80 means under said head, pressing means in said head, means for operating said pressing means toward and away from said working means, a driving shaft, a clutch for connecting said driving shaft with said working means, mechanism operatively connected with the means for operating said pressing means acting to throw in said clutch after said pressing means has been withdrawn from said working means, said throw-out 85 mechanism including a lever connected to said clutch, and an abutment on said presser operating means for engaging and actuating said lever.

In testimony whereof I affix my signature. 90
GOTTFRIED RAUSCH.
